United States Patent Office

Des. 229,517

Patented Dec. 4, 1973

229,517

BOTTLE SLING

John C. Wilson, Anaheim, Calif., assignor to Baxter Laboratories, Inc., Morton Grove, Ill.

Filed May 22, 1972, Ser. No. 255,932

Term of patent 14 years

Int. Cl. D24—04

U.S. Cl. D83—8 R

FIG. 1.

FIG. 2.

FIG. 5.

FIG. 3.

FIG. 4.

FIG. 6.

FIG. 1 is a perspective view of a bottle sling showing my new design, the broken lines representing the bottle are shown for illustrative purposes only;

FIG. 2 is a perspective view of the bottle sling in an alternate open condition;

FIG. 3 is a front elevation of FIG. 1;

FIG. 4 is a side elevation thereof;

FIG. 5 is a top plan view thereof; and

FIG. 6 is a bottom plan view thereof.

I claim:

The ornamental design for a bottle sling, as shown and described.
